UNITED STATES PATENT OFFICE

ROBERT BRUCE, OF WELLINGTON, KANSAS

HASP FASTENER

Application filed October 14, 1929. Serial No. 399,590.

This invention has reference to hasp fasteners, and more particularly to hasp fasteners employed in connection with freight car doors.

5 The primary object of the invention is to provide a fastener which will automatically adjust itself, so that it may align with the keeper with which the hasp fastener is used to insure against binding of the fastener 10 should the door on which the hasp is supported, sag.

A further object of the invention is the provision of means for supporting the hasp, when the same is in its inactive position.

15 With the foregoing and other objects in view, which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 Referring to the drawing:

Figure 1 is an elevational view of a hasp constructed in accordance with the invention.

Figure 2 is a sectional view taken on line 2-2 of Figure 1, the hasp being shown in 30 dotted lines as in its inactive position.

Figure 3 is a perspective view of the hasp and its keeper.

Referring to the drawing in detail, the reference character 5 designates the hasp supporting plate, which is provided with openings to receive suitable securing screws, whereby the supporting plate may be secured to the door of a box car.

40 The reference character 6 designates a rod which is secured to the supporting plate 5, the rod being provided with an offset portion 7 that extends beyond the front face of the plate, to provide a clearance for the hasp proper which is indicated by the reference character 8.

The hasp 8 is provided with an elongated opening 9 through which the rod 6 extends, the opening 9 being elongated so that the hasp 45 may move transversely of the supporting

plate, to permit the hasp to be moved into co-operative relation with the keeper 10 with which the hasp is used.

As shown, the hasp 8 is provided with a raised shoulder 11 adapted to rest against one side of the keeper 10, the shoulder being provided with an opening to receive the lock or seal used in connection with car door fasteners. The free end of the hasp 8 is turned inwardly as at 12, providing a finger piece 60 which is spaced from the keeper 10, so that a person may grip the finger piece and move the hasp to its active or inactive position.

Openings are formed in the base 13 of the keeper, and provide means whereby securing 65 screws may be positioned to secure the keeper against movement. Extending laterally from the supporting plate, is a rest 14 which is provided with an upstanding portion so arranged that the hasp 8 may be swung to a position 70 between the upstanding portion and supporting plate, to hold the hasp in its inactive position and prevent damage to the hasp and its supporting rod, due to the hasp being jammed against the keeper, when the door is 75 moved to its closed position.

From the foregoing it will be obvious that due to this construction, the hasp may be lowered, so that the opening thereof through which the keeper extends, may be brought 80 to a position directly over the keeper at all times regardless of whether or not the door sags on its tracks, and thereby eliminating the necessity of raising the door by the use of a crowbar positioned under the lower edge 85 thereof, which often becomes necessary when doors get out of alignment.

I claim:

In a hasp for sliding closures, a supporting plate having bearing openings, a vertical rod, 90 the ends of the rod being held in the bearing openings, said rod having an offset portion extending from the inner ends of the bearings, to restrict movement of the rod, a hasp having an enlarged end portion formed with an elongated opening, extending throughout the length of the enlarged portion to receive the rod, a keeper having flat side faces, an apertured flange extending from the hasp and adapted to lie against the keeper to receive a 100

lock positioned in the keeper, and a hook member extending upwardly from the supporting plate to receive the hasp when the hasp is in its inactive position.

5 In testimony that I claim the foregoing as my own, I have hereto affixed my signature.

ROBERT BRUCE.
